VARIABLE LIQUID RESISTANCE APPARATUS

Norbert R. Benchemoul, Paris, France

Application September 22, 1950, Serial No. 186,252
In France September 29, 1949

4 Claims. (Cl. 201—57)

1

The present invention concerns an apparatus comprising, within an enclosure full of liquid, at least two immersed electrodes having parallel surfaces and liable to be relatively displaced parallelly to one another, so that the surfaces of these electrodes opposite one another can be varied, without varying their distance apart. As a result the liquid resistance between these electrodes varies accordingly.

In a preferred embodiment, the electrodes are constituted by coaxial revolution surfaces and are rotatable relatively to one another about their common axis.

Such an apparatus can be used either as a source of heat owing to the calories evolved in the liquid by Joule's effect, or as a mere rheostat, for instance as starting rheostat or regulating rheostat.

Whatever be the applications of this apparatus, it may be of advantage, for the purpose of evacuating the calories evolved, to circulate the liquid either along a closed circuit, for instance through a radiator, or along an open circuit in which case the apparatus operates as the essential element of a heating cock.

In order to increase the operative surfaces of the electrodes without unduly increasing the size of the enclosure containing the liquid, it is convenient to imbricate the electrodes, so that both sides of any one electrode can be brought opposite the corresponding sides of the other electrode. The active portions of the electrodes are thus arranged in staggered formation.

The apparatus of the invention is particularly convenient in the case of alternating currents as they do not practically cause electrolysis.

In the case of single-phase current, the apparatus can merely comprise two electrodes one of which is movable, the other being preferably stationary.

In the case of multiphase current, it is possible to use a number of single-phase apparatus equal to the number of phases, to connect them across the phases or between the phases and a neutral point, and to link mechanically these apparatus in such a way that the relative positions of the electrodes of all the apparatus be the same at the same time.

It is also possible to resort to a star-coupling by using a number of stationary electrodes equal to the number of phases, these electrodes being regularly distributed about the axis of the enclosure, and an equal number of movable electrodes electrically and mechanically connected

2

to each other, these latter electrodes being also regularly distributed about said axis.

In this latter case, each electrode which conveniently assumes the shape of a cylindrical portion, extends over an arc of π/n (n being the number of phases) and the stationary electrodes as well as the movable ones are separated by angular intervals of π/n .

Other objects and advantages of the invention will be apparent during the course of the following description. In the accompanying drawing forming a part of this application and in which like numerals are employed to designate like parts throughout the same,

15 Fig. 1 is a vertical section through a single-phase apparatus, taken along line I—I of Fig. 2,

Fig. 2 is a bottom plan view, the adjusting knob being removed for clearness sake,

Fig. 3 is a top plan view of the apparatus,

20 Fig. 4 illustrates the apparatus fitted up on a cock, the latter being shown in vertical section,

Fig. 5 is a perspective view of a three-phase rheostat according to the invention,

Figs. 6 and 7 are plan views showing the connecting system and the adjusting system of this rheostat,

Fig. 8 is a diagram showing the electrical and mechanical connections of the stationary electrodes and of the movable ones, and

25 Fig. 9 is a perspective view with diametrical section of the rheostat of Figs. 5 to 8.

As shown in Figs. 1, 2 and 3, the single-phase apparatus comprises a cylindrical casing 1 made of insulating and liquid-tight material, open at one end 1a, and whose bottom 1b has a central hole 2 around which a circular groove 3 is provided. This central hole 2 extends downwards (on Fig. 1) through a semi-cylindrical shoulder 4.

The central hole 2 contains a conducting sleeve

30 5 the lower part of which is hollow and engages a knob 6 of insulating material. Half of the outer surface of this part 5a is covered by the shoulder 4, the other half (located towards the left-hand side of Fig. 1) being uncovered. A semi-cylindrical conducting strip 7 is applied on this free half of 5a, by means of a pusher 8 (Fig. 2) urged by a spring (not shown) lying inside a cylinder 9 secured to the casing 1. The strip 7 is connected to a terminal 10 screwed into the

35 bottom 1b of the casing and provided with a tightening nut 11.

On the upper surface of the bottom 1b and of the sleeve 5, there is provided a shaped tightness joint 12 held in position by a ring 13 having a circular rib 13a fitting the groove 3. The circu-

lar flange 15 of a semi-cylindrical metal plate 16 is applied, through a washer 14, on this ring 13. The sleeve 5, the ring 13, the washer 14 and the flange 15 are all secured to the knob 6 by means of a stainless metal screw 17.

The upper edge (Fig. 1) of plate 16 is turned over and secured, for instance by welding, to the edge also turned over of a further semi-cylindrical metal plate arranged coaxially to and opposite the former one.

Between these two plates 16 and 18, another semi-cylindrical coaxial plate 19 is inserted; its lower edge 19a is turned over and applied on the turned over lower edge 20a of a further semi-cylindrical coaxial plate 20. Hence the two pairs of plates, 16 and 18 on the one hand, 19 and 20 on the other hand, are arranged in staggered formation and coaxially to each other and to the casing 1.

Plates 19-20 are secured, by means of a screw 21, to a metal terminal 22 extending right through the bottom 1b of the casing and provided with a protruding threaded rod 23 carrying a nut 24 tightened upon a washer 25.

The part of the apparatus above the knob 6 is wrapped in a metal sheathing 26 which can be enamelled and used as embellisher.

The apparatus operates as follows:

The terminals 10 and 22 are connected to a source of current, for instance the mains, and the plates 16-18 and 19-20 are thus energized. As the casing 1 contains a conducting liquid, water for example, the plates 16-18 and 19-20 constitute electrodes connected by the liquid mass lying therebetween. The electrode 16-18 being fast with knob 6, its position in casing 1, is adjustable. Whatever be its position, electrode 16-18 is always live owing to the permanent contact between strip 7 applied by pusher 8 on the metal surface 5a of sleeve 5 which acts as a collector-ring. It is to be noted that no current flows through the resilient pusher 8 which merely plays a mechanical part. It is thus less liable to get damaged than if it were used as a terminal for the purpose of avoiding strip 7.

It is to be further noted that the tightening nuts 11 and 24 of the terminals, as well as the collector-ring 5a are located in a liquid-tight compartment between the bottom 1b of the casing and the knob 6, thus avoiding any danger of electric leakages and of undue heating.

As known, the value of liquid resistance is proportional to the surfaces facing one another, of the electrodes dipping into this liquid, and inversely proportional to the distance between these electrodes. It is obvious that, in the case of the above apparatus, the value of the liquid resistance will depend on the relative position of the electrodes 16-18 and 19-20. In particular, it will vary, in a continuous way, from a minimum value corresponding to the position for which the electrodes are completely engaged into one another, to a maximum value corresponding to the position for which the electrodes are diametrically opposite. Thus the thermal output of the apparatus varies between two predetermined limits.

In an embodiment of the invention (Fig. 4), this apparatus is fitted up on a cock adapted to this purpose. The water inlet a is controlled by a gate-valve b actuated as usual by means of a knob g. The water flows, through a duct c, into the central portion of the apparatus. This water, after having been heated, flows out through the conduit d whose diameter is smaller than that of duct c, and through the anti-splash nozzle e. Of

course, the feed-current of the apparatus must be switched off as soon as the tap is turned off. Nevertheless, in case of absentmindedness, most of the water remaining inside the apparatus is expelled by air stored up at its upper part and the remainder being still heated is evaporated, the steam issuing through conduit d and nozzle e. When this remainder has evaporated, the current is automatically cut off.

The body-portion f of the cock shown in the drawing is conveniently made of insulating material and the nozzle e is internally lined with an insulating layer of enamel. This results in an important drop in voltage due to the length of the water columns flowing into and out of the apparatus. Indeed the water flowing into and out of the apparatus follows relatively long paths along ducts a-c and conduits d-e respectively. Thus, if slight current leakages occur because of an insulation or a contact defect, a complementary safety is ensured by the voltage drop along these water columns, thus avoiding even a slight danger of electrocution.

In the example of Fig. 4, the axis of the apparatus is horizontal, the stationary electrode lying in the lower half of the casing. This disposition is particularly convenient for it enables to keep the power consumption to a substantially constant value, whatever be the water output. It is known indeed that the resistivity of water varies inversely as its temperature. Besides, the temperature of water depends on its flowing speed, and more specifically on the time during which it is subjected to an electric current, i. e. on the time during which it flows between the electrodes. Hence when the tap is turned further on, the temperature of the water decreases and its resistivity rises; as a result the current tends to decrease. However, an increase in flow corresponds to an increase of the immersed surfaces of the electrodes since the water level rises in the casing (this is due to the fact that the diameter of the inlet duct c is greater than the diameter of the outlet conduit d). Hence the resistance of water decreases and the current tends to increase. Practice shows that these two opposite tendencies substantially balance and the current remains constant.

If, on the other hand, it is aimed at achieving a uniform temperature independent of the flow, it is sufficient to link the gate-valve b to the movable electrode. This can be done through various known means (not shown): e. g. a gear-train between knob g and knob 6, or else a direct connection of knob g to the movable electrode thus doing without knob 6. The apparatus of the invention is particularly well adapted for such a purpose as its electrical adjustment is effected by rotating an electrode, the control of the flow being also effected by a rotary member.

Thus in increasing the flow of water, the movable electrode is simultaneously driven in the direction corresponding to a decrease in resistance and hence to an increase of absorbed power, so as to keep constant the temperature of water. In the case of a decrease in flow, the opposite phenomenon occurs.

Obviously the above apparatus can have other applications than those described with reference to Fig. 4. It can be fitted up on a heating element or water radiator of any type, the water being circulated by means of a pump or merely by thermo-siphon.

Furthermore, the apparatus can be used, not as a heating element, but merely as a rheostat.

The casing 1 must then be hermetically sealed after having been filled with an appropriate conducting liquid, or else if it is desired to ensure proper evacuation of the calories evolved by the rheostat, the liquid can be permanently circulated, preferably along a closed circuit, through a cooler.

The applications of the apparatus as a rheostat do not differ in their principle from the applications of this same apparatus for heating a liquid.

Figs. 5 to 9 show a form of an apparatus according to the invention, which is used as a three-phase rheostat.

This rheostat which is shown in perspective view in Figs. 5 and 9, comprises an insulating cylindrical casing 27 similar to casing 1 of Fig. 1. Above this casing 27, there is provided a tank 28 tightly sealed by a plug 29. The liquid mass stored in this tank limits the rise in temperature of the apparatus. Cooling fins 30 are radially secured to this tank. The casing 27 carries a base-flange 31 provided with three terminals 32 designed to be connected to a three-phase circuit. A stationary circular plate 33 of insulating material and a further circular plate 34 coaxial and rotatable relatively to the former one, are located underneath—the flange 31. The latter plate 34 which is also made of insulating material is actuated by means of an arm 35 secured in 36 underneath it.

The plate 33 carries on its lower side, three studs 37 (Figs. 7, 8 and 9) electrically connected to the terminals 32. Each stud is integral with a resilient metal strip 38 shaped as an arc of circle of about 60°; the three strips 38 separated by arcs of 60°, are fitted up in a circular groove 39 on the surface of plate 33, so as to slightly protrude. Opposite each strip 38, a further strip 40 also shaped as an arc of circle concentric to and of same angular size as the former one, is located. These strips 40 are located in a circular groove 41 and connected, through bolts 42, to the three stationary and independent electrodes 43 which extend over sectors of 60° and are separated by intervals of the same value. The movable electrodes 46 integral with a common flange 60, have the same angular size as the stationary electrodes and are coaxial thereto. The flange 60 is secured to a shaft 44 which crosses the bottom of casing 27, the base-flange 31 and the plate 33. A shoulder of this shaft ensures tightness by cooperating with a washer 61. This shaft ends at its lower part in a square portion 45 which fits the centre of plate 34.

The latter comprises, on its upper side (opposite side that of plate 33 shown in Fig. 7), three pistons 47 arranged at 120° to each other and connected together by a wire 48 embedded within the plate. These pistons 47 are urged by springs 62 (Fig. 9) and protrude above the surface of this plate 34. The latter further carries three contact brushes 49 (for instance curved strips), insulated from each other and arranged on the radii passing through the pistons 47.

The studs 37 of the plate 33 and the pistons 47 of the plate 34 are located on circumferences of the same radius. Furthermore the brushes 49 are so arranged and their size is such that they lie across the annulus formed by the grooves 39—41 of plate 33.

In the position illustrated by Fig. 8, the brushes 49 not being in contact with the strips 38—40, all the electrodes are out of circuit. A slight rotation of the plate 34 brings about this

contact thus energizing the electrodes which remain live during the whole displacement of the brushes 49 from one end of strips 38—40 to the other, the movable star-coupled electrodes 46 moving then from the position of Fig. 8 (maximum resistance) to the position 60° away for which they are entirely opposite the stationary electrodes 43 (minimum resistance). The pistons 47 then come into contact with the studs 37 which are thereby short-circuited owing to the wire 48.

The rotation of plate 34 is limited by stops 50—51 (Fig. 7) located on the path of the pistons 47 in positions corresponding to the switching off and to the short-circuiting of the rheostat.

The slight current leakages occurring directly between the stationary electrodes 43 do not upset the phase equilibrium of the circuit. It can be shown that they are equivalent to three large triangle-coupled resistors giving rise to equal and weak voltage drops. Furthermore the heating of the liquid is limited owing to the large cooling surfaces of the tank 28 and of the fins 30.

Obviously the above three-phase apparatus can be used as a heating element similarly to the apparatus described with reference to Figs. 1 to 4, just as the latter can be used as a single-phase rheostat.

The apparatus may be adapted to any multiphase supply circuit, by altering, in accordance with the number of phases, the number and size of the various members. Thus for an n -phase circuit, the apparatus will comprise n pairs of electrodes, one electrode of each pair being stationary and the other one movable, all the movable electrodes being simultaneously displaced. These electrodes will be formed by cylindrical angular sectors of π/n separated by equal intervals. They may comprise a single surface (as in the example of Fig. 8) or several surfaces in staggered formation (as in the example of Figs. 1 and 9).

In the case of multiphase currents, it is of course possible to link mechanically several apparatus as that shown in Figs. 1 to 3, each of them being connected either across the phases or between a phase and a neutral point.

It is to be understood that the form of the invention herewith shown and described is to be taken as a preferred example of the same and that various changes in the shape, size and arrangement of parts may be resorted to without departing from the spirit of the invention or the scope of the subjoined claims.

What I claim is:

1. In a variable liquid resistance apparatus, the combination of at least two electrodes constituted by coaxial portions of revolution surfaces, means for relatively rotating said electrodes about their common axis, at least one contact sector fast with and coaxial to one of said electrodes, and at least one contact member in sliding contact with said sector and fast with the other one of said electrodes.

2. In a variable liquid resistance apparatus, the combination of a pair of electrodes constituted by coaxial portions of revolution surfaces, means for rotating one electrode of said pair about its axis, a cylindrical contact sector fast with and coaxial to said latter mentioned electrode, an electrical connection between said latter mentioned electrode and said sector, a resilient metal strip located around part of said cylindrical sector and fast with the other electrode of said pair, a resilient pusher member adapted to urge said strip into sliding contact with said cylindrical

sector, and a terminal electrically connected to said strip.

3. In a variable liquid resistance apparatus, the combination of a plurality of pairs of electrodes constituted by coaxial portions of revolution surfaces, means for simultaneously rotating one electrode of each of said pairs about their common axis, a pair of coaxial bridge-like contact sectors fast with and coaxial to each one of the other electrodes of said pairs of electrodes, a contact member in sliding contact with both sectors of each one of said pairs of sectors and fast with the former mentioned electrodes of said pairs of electrodes, means for electrically connecting one sector of each one of said pairs of sectors to each one of said other electrodes, and a plurality of terminals electrically connected to each one or the other sectors of said pairs of sectors.

4. In a variable liquid resistance apparatus, the combination of a plurality of pairs of electrodes constituted by coaxial portions of revolution surfaces, means for simultaneously rotating one electrode of each of said pairs about their common axis, a pair of coaxial bridge-like contact sectors fast with and coaxial to each one of the other electrodes of said pairs of electrodes, a contact member in sliding contact with both sectors of each one of said pairs of sectors and

fast with the former mentioned electrodes of said pairs of electrodes, means for electrically connecting one sector of each one of said pairs of sectors to each one of said other electrodes, a plurality of terminals electrically connected to each one of the other sectors of said pairs of sectors, said terminals being regularly arranged around the axis of said electrodes, and a stud fast with each one of said former mentioned electrodes, said studs being electrically connected to each other and being arranged regularly around the axis of said electrodes and at the same distance from this axis as said terminals.
